CAN HOLDER OR THE LIKE

Douglas B. Hansen, 3497 Wexford Road, Lansing, Mich.

Filed Nov. 13, 1961, Ser. No. 67,486

Term of patent 14 years

(Cl. D44—21)

FIGURE 1 is a perspective view of a can holder with the cap in open position showing my new design.

The can shown in broken lines is for illustrative purposes only.

I claim:

The ornamental design for a can holder or the like, as shown and described.
